(57) **CLAIM**

The ornamental design for a network communication housing, as shown and described.

DESCRIPTION

FIG. 1 is an isometric view of the network communication housing of this invention.

FIG. 2 is a left-side elevational view of the network communication housing of FIG. 1.

FIG. 3 is a right-side elevational view of the network communication housing of FIG. 1.

FIG. 4 is a top view of the network communication housing of FIG. 1.

FIG. 5 is bottom view of the network communication housing of FIG. 1.

FIG. 6 is a front view of the network communication housing of FIG. 1.

FIG. 7 is a rear view of the network communication housing of FIG. 1; and,

FIG. 8 is an isometric view of the network communication housing of FIG. 1 in an open configuration.

1 Claim, 6 Drawing Sheets

FIG. 1

FIG. 2

FIG. 3

FIG. 4

FIG. 5

FIG. 6

FIG. 7

FIG. 8
